(57) **CLAIM**

The ornamental design for a rounded edge dual screen mobile device, as shown and described.

DESCRIPTION

FIG. 1 is a front isometric view of the rounded edge dual screen mobile device of the present invention;

FIG. 2 is a back isometric view of the invention of FIG. 1;

FIG. 3 is a front view of the invention of FIG. 1;

FIG. 4 is a back view of the invention of FIG. 1;

FIG. 5 is a side view of the invention of FIG. 1, as seen from the bottom side of FIG. 3;

FIG. 6 is a side view of the invention of FIG. 1, as seen from the top side of FIG. 3;

FIG. 7 is a side view of the invention of FIG. 1, as seen from the left side of FIG. 3; and,

FIG. 8 is a side view of the invention of FIG. 1, as seen from the right side of FIG. 3.

The broken lines showing various ports and buttons form no part of the claimed design.

1 Claim, 6 Drawing Sheets
